ATTORNEY

UNITED STATES PATENT OFFICE

STEPHEN VORECH, OF WILMERDING, PENNSYLVANIA, ASSIGNOR TO THE WESTINGHOUSE AIR BRAKE COMPANY, OF WILMERDING, PENNSYLVANIA, A CORPORATION OF PENNSYLVANIA

STRAINER BAFFLE

Application filed March 4, 1930. Serial No. 433,057.

This invention relates to air purifiers and more particularly to that type for use in vacuum brake equipment.

The principal object of my invention is to provide a cover or baffle device for an air strainer which will prevent dirt and moisture from being deposited directly upon the air inlet portion of the strainer and which, at the same time, will permit an air stream to flow freely therethrough to the strainer.

A further object of my invention is to provide a cover or baffle device for an air strainer which will separate large particles of matter foreign to air from the air stream flowing through said cover to the strainer.

In the accompanying drawings; Fig. 1 is a longitudinal sectional view taken horizontally through a portion of an automotive vacuum brake equipment embodying my invention; Fig. 2 is an enlarged detail plan view of one portion of the cover device; Fig. 3 is a cross sectional view of the same taken on the line 3-3 of Fig. 2; Fig. 4 is an enlarged detail plan view of another portion of the cover device; and Fig. 5 is a cross sectional view of the same taken on the line 5-5 of Fig. 4.

In Fig. 1 of the drawings I have shown my invention applied to an automotive vacuum brake equipment of the usual well known type, only so much of the equipment being illustrated in the drawings as is deemed necessary for a clear understanding of the invention.

The portion of the automotive vacuum brake equipment which is illustrated comprises a casing 1 having a piston 2 mounted therein, which piston is operatively connected to the usual push rod 3 through the medium of a lever 4, pivotally anchored to the casing, and a chain 5, said lever, chain and one end of the push rod being contained in a chamber 6 at one side of the piston 2, which chamber is constantly connected to the atmosphere through a passage 7 formed in the casing 1.

Leading from the chamber 8 at the other side of the piston 2 is a pipe 9 through which air from the chamber may be expelled in the usual manner to create a partial vacuum at this side of the piston.

For the purpose of cleansing the air flowing from the atmosphere to the chamber 6, there is interposed in the passage 7, an air strainer of the usual type having spaced inner and outer perforated plates 10 and 11 respectively, between which there is a suitable air cleaning medium, such as pulled curled hair or the like. The outer edge portion of the inner strainer plate 11 engages an inwardly directed annular flange 12 formed integral with the casing 1.

For the purpose of preventing moisture and other matter foreign to air from being deposited directly into the strainer and to assist in cleansing the air stream flowing into the chamber 6, I provide a cover or baffle device 13 which rests on the outer plate 10 of the strainer, said device comprising a plate 14 to which is secured a cap member 15.

The plate 14 has a flat annular outer portion 16 having a plurality of rectangular openings 17 formed therein. This plate has a central opening 18 which is defined by an annular baffle wall or flange 19 which extends outwardly some distance beyond the plane of the flat portion 16.

The cap member 15 has a top or cover portion 20 and an inwardly directed annular wall 21, said cover portion and wall being preferably integral. The wall 21 is provided with spaced lugs 22 which, in assembling the baffle device, are inserted in the openings 17 in the plate 14. The outer ends of these lugs project through the plate 14, and to secure the cap 15 and plate 14 together, the projecting ends of the lugs are bent into engagement with one side of the plate 14. When the lugs are thus bent, the edge portions of the wall 21 engage the other side of the plate 14.

The wall 21 is provided with notches 23 which are alternately spaced with the lugs 22 and which, together with the plate 14, define openings through which an air stream is adapted to flow to a clear air space 24 which is defined by the baffle flange 19 of the plate 14 and the wall 21 of the cap member 15.

There is also a clear air space between the inner surface of the cover portion 20 of the cap member 15 and the outer edge of the baffle

flange 19 so that air from the air space 24 is free to flow through the opening 18 to the strainer. The notches 23 and the baffle flange 19 are of such lengths and are so disposed 5 that the air stream entering the air space 24 will not flow directly through the space between the top of the flange 19 and the cover portion 20, but will first strike against the flange 19 and then flow through this space 10 and opening 18 to the strainers.

When the cover or baffle device 13 is mounted in its proper position in the casing, as shown in Fig. 1, the bent-over lugs 22 rest against the outer surface of the perforated 15 strainer plate 10 and thus space the flat annular portion 16 of the plate 14 away from the outer surface of the plate 10, so that this portion 16 offers substantially no obstruction to the flow of the air stream to the strainer.

20 The device 13 is removably held in its proper position in the casing and against the strainer by a snap ring 25 which engages the flat portion 16 of the plate 14 and also engages the casing within a circular groove.

25 It will be seen that the cover or baffle device 13 is well adapted to prevent matter foreign to air from being deposited directly on the inlet end of the strainer and to permit the free flow of air therethrough to the 30 strainer.

Air flowing from the atmosphere to the chamber 6 passes through the notches 23 in the wall 21 of the cap member 15, clear air 35 space 24, over the outer edge of the baffle flange 19, through the opening 18 in the plate 14 and finally through the strainer, thus forming a tortuous passageway which effectively prevents moisture and dirt from being directly deposited into the strainer.

40 It will also be seen that some of the moisture and other foreign matter carried into the device 13 by an air stream flowing therethrough will impinge on the outer surface of the baffle flange 19 and condense thereon 45 or be otherwise separated from the stream, and by the force of gravity, the matter separated from the stream will drop out of the device, thus rendering the device self cleaning.

50 By the use of the snap ring 25 the removal and replacement of the device 13 is rendered very easy.

While one illustrative embodiment of the invention has been described in detail, it is 55 not my intention to limit its scope to that embodiment or otherwise than by the terms of the appended claims.

Having now described my invention, what I claim as new and desire to secure by Letters Patent, is:

60 1. A cover for an air strainer comprising a plurality of plates forming a passageway through which an air stream flows to said strainer, and lugs on one of said plates extending through and bent into engagement

with the other of said plates to secure said plates together.

2. A cover for an air strainer comprising a plurality of connected plates, one of said plates having an annular outwardly extending wall defining a central opening therethrough, and the other of said plates comprising a cover portion extending over said opening and also comprising an inwardly extending wall having openings formed therein for the passage of air therethrough, said walls and cover portion defining a tortuous passageway through which an air stream flows from the atmosphere to the air strainer.

In testimony whereof I have hereunto set my hand, this 28th day of February, 1930.

STEPHEN VORECH.
